FLEXIBLE PLASTIC TRIMMING OR THE LIKE

Jean Frechtmann, New York, N. Y.

Application March 18, 1949, Serial No. 1,467

Term of patent 7 years

(Cl. D87—3)

To all whom it may concern:

Be it known that I, Jean Frechtmann, a citizen of no country, residing in New York city, county of New York, and State of New York, have invented a new, original, and ornamental Design for a Flexible Plastic Trimming or the like, of which the following is a specification, reference being had to the accompanying drawing, forming part thereof, wherein,

Figure 1 is a front elevational view of a flexible plastic trimming showing my new design.

Figure 2 is a side elevational view of the flexible plastic trimming, and,

Figure 3 is a front perspective view of the flexible plastic trimming shown in Figures 1 and 2.

I claim:

The ornamental design for a flexible plastic trimming or the like, substantially as shown.

JEAN FRECHTMANN.
